UNITED STATES PATENT OFFICE.

WILLIE GEORGE MILLS AND CHARLES TURNER PACKARD, OF IPSWICH, ENGLAND,
ASSIGNORS TO EDWARD PACKARD AND COMPANY, LIMITED, OF IPSWICH,
ENGLAND.

CHAMBER USED IN THE MANUFACTURE OF SULFURIC ACID

1,312,741.

Specification of Letters Patent. Patented Aug. 12, 1919.

Application filed July 31, 1918. Serial No. 227,572.

To all whom it may concern:

Be it known that we, WILLIE GEORGE MILLS and CHARLES TURNER PACKARD, subjects of the King of Great Britain, both residing at Bramford Works, Ipswich, England, have invented new and useful Improvements in the Chambers Used in the Manufacture of Sulfuric Acid, of which the following is a specification.

10 This invention relates to apparatus for the manufacture of sulfuric acid of the type described in our Patent No. 1,112,546. This patent describes a lead chamber of the shape of a frustum of a pyramid or preferably 15 of a cone which is the limiting case of a pyramid, and the chamber is supported by rings connected to a framework and to the chamber to form troughs for the collection of cooling water flowing down the outside of 20 the chamber.

We now provide the chamber with a cooling lead shaft or tube which may also be supported by rings connected to the framework and to the shaft to form troughs which 25 may also be utilized for cooling the inside of the shaft by the flow of water.

The shaft may be of the shape of a frustum of a cone, the walls sloping inward from top to bottom in the reverse way to 30 that of the chamber itself.

The lead chamber itself may be of the shape of the frustum of a cone. Such chambers may be provided with one or more internal cooling shafts as above described, 35 and are cooled in the manner described in the above mentioned patent.

Preferably, however, in place of drawing off the water from each trough through drain pipes, the water is allowed to pass 40 through orifices into a gutter surrounding the trough, while the gutter is provided at the top with notches through which the water trickles.

The gas is preferably delivered into the 45 chamber through a single pipe set at such an angle that the gas is directed toward the floor of the chamber.

The invention is illustrated in the accompanying drawings in which Figure 1 is a sectional elevation, and Figs. 2 and 3 are respectively a section and elevation of the gutter and its support.

In the drawings 1 is the chamber carried

by a framework 2. 3 are rings which carry lead rings 4; the top portion of the double strip forming the ring 4, is solid except for orifices 6 and forms a trough 7 (see Fig. 2) and its edges are burned both to the chamber wall and to the ring 8; the lower portion 5 of the strip is cut away at intervals and 60 its edges are also burned to the chamber wall and to the ring 3. 8 is a gutter surrounding the bottom of the trough 7; the top edge of the gutter is saw cut and the teeth 9 so formed are then twisted at an 65 angle of 45°.

10 is the central cooling shaft carried by framework 11 and provided with rings 12 and 13 similar to the rings 3 and 4 and also with gutters similar to the gutters 8.

15 is the inlet for the gas which is directed toward the floor of the chamber and 16 is the outlet for the gas.

Water is supplied to the ceiling 17 of the chamber and shaft or also if desired at intervals by a pipe 18 and the ceiling 17 may slope from the central shaft to the wall of the chamber.

What we claim is:—

1. In apparatus for the manufacture of 80 sulfuric acid, the combination of a chamber to which the gas to be treated is admitted, a cooling shaft within the chamber, a frame within said cooling shaft, means for supplying water to the inside of the shaft, means supported by the frame for receiving at various elevations water supplied to the shaft, and means for supplying a cooling agent to the outside of the chamber.

2. In apparatus for the manufacture of 90 sulfuric acid, the combination of a chamber to which the gas to be treated is admitted, a cooling shaft within the chamber, means for supplying water to the inner surface of the shaft, gutters within the shaft for receiving the descending water, and means for supplying a cooling agent to the outside of the chamber.

3. In apparatus for the manufacture of 100 sulfuric acid, the combination of a chamber to which gas to be treated is admitted, a cooling shaft within the chamber which tapers inward from top to bottom, means for supplying a cooling agent to the shaft, and means for supplying a cooling agent to 105 the outside of the chamber.

4. In apparatus for the manufacture of sulfuric acid, the combination of a chamber to which gas to be treated is admitted and which tapers upwardly from its bottom, a cooling shaft within the chamber which tapers downwardly from top to bottom, means for supplying a cooling agent to the inside of the shaft, and means for supplying a cooling agent to the outside of the chamber.
5. In apparatus for the manufacture of sulfuric acid, the combination of a chamber to which gas to be treated is admitted, means for supplying a cooling agent to the outside of the chamber, a trough applied to the outside of the chamber and having orifices through which the cooling agent passes, and
6. In apparatus for the manufacture of sulfuric acid, the combination of a chamber to which the gas to be treated is admitted, means for delivering a cooling agent to the outside of the chamber, a trough applied to the outside of the chamber and having outlet orifices, and a notched gutter on the outside of the chamber to which the trough delivers.
7. In apparatus for the manufacture of sulfuric acid, the combination of a chamber to which the gas to be treated is admitted, means for delivering a cooling agent to the outside of the chamber, a trough applied to the outside of the chamber and having outlet orifices, and a notched gutter on the outside of the chamber to which the trough delivers.

In testimony that we claim the foregoing as our invention, we have signed our names this 25th day of June, 1918.

WILLIE GEORGE MILLS.
CHARLES TURNER PACKARD.
